(57) **CLAIM**

The ornamental design for a tea filter, as shown and described.

DESCRIPTION

FIG. 1 is a front elevational view of the tea filter, the rear view being the mirror image of the tea filter;

FIG. 2 is a perspective view thereof;

FIG. 3 is a side elevational view of the tea filter as seen from the right side of FIG. 1;

FIG. 4 is a perspective view of the tea filter in an open position; and,

FIG. 5 is a perspective view of the tea filter in a partially closed position.

The broken line showing of a tag is for the purpose of illustrating environment and forms no part of the claimed design.
